FORMATION OF KNOTS, PARTICULARLY
WEAVERS' KNOTS

Max Poege, Uster, near Zurich, Switzerland

Application December 17, 1935, Serial No. 54,914
In Germany August 26, 1933

16 Claims. (Cl. 289—3)

In this textile industry various processes and appliances have been suggested for the production of knots, more particularly weavers' knots, which tie the knot in a more or less complicated manner. There are appliances which twine the thread ends round one another several times in tying the knot by rotating a so-called binding bill or beak, so that the main threads, after the knotting operation, are still twisted round several times.

A further very serious disadvantage of all the known knotting processes and appliances consists in the fact that knot-forming parts of the apparatus execute advancing and receding movements during the formation of the knot. This however adversely affects the simplicity, reliability and quickness of the knotting operation.

Finally, with many appliances it is not possible to knot threads of different thicknesses and different degrees of elasticity with one another.

All these defects are eliminated by the present invention, in that according to the new process the thread ends to be knotted to one another are twined round two intersecting bar-shaped members, preferably a vertical withdrawable mandrel and a horizontal holding member, in such a way that firstly both the thread ends are laid beside the mandrel upon the holding member, then one end is placed round the mandrel and the other end round the holding member and mandrel to form a loop, after which both ends are carried through between the primary threads, which are held fast, whereupon the end that is put round the holding member (or both ends) is (or are) firmly gripped by the latter, while the loop put round the holding member, after withdrawal of the mandrel, is pulled off the holding member and stripped over the thread end that is held fast.

In order to carry out this process an appliance is used according to the invention, which consists essentially of a withdrawable mandrel, a cutting and holding appliance formed of two cutting jaws and a gripping jaw, a thread placer or introducing means movable in an arcuate path, and a helical thread guide. These parts of the appliance are known individually or in other combinations in this or a similar form. What is essential in the new appliance is the particular manner in which the members are arranged relatively to one another and the particular manner in which they co-operate with one another. With this appliance it is possible in a simple manner to place the thread ends in the appliance simultaneously and parallel to one another with one hand. All the knot-forming members move

in one direction only during the knotting, so that the knot can be very quickly and reliably made. After the knotting the tied threads can be taken out of the appliance in an untangled condition.

The method of tying the knots and the appliance for carrying out this method are illustrated by way of example in the accompanying drawings, in which

Figures 1 to 5 show the knotting operation according to the new method at various stages of the work;

Figure 6 shows a finished weaver's knot made by this method;

Figure 7 shows a modification of the weaver's knot;

Figure 8 shows in front elevation an appliance for carrying out the method according to the invention, this appliance being shown approximately in its natural size;

Fig. 9 shows a plan of the appliance; and

Figure 10 shows the appliance in side elevation looking in the direction of the arrow A in Figure 9;

Figure 11 is a back view of the appliance, partly in section, with the upper portion of the casing removed;

Figure 12 shows the appliance in section through the casing on the line XII—XII in Figure 9;

Figure 13 is a side view of the appliance, looking in the direction of the arrow B in Fig. 9, with the casing removed;

Figures 14 and 15 show details of the appliance on a larger scale;

Figure 16 shows a section through certain details on the line XII—XII in Figure 9; and

Figure 17 shows a portion of the appliance illustrated in Figure 13 on a greatly enlarged scale.

In Figures 1 to 5 are represented the most important stages in the method of knotting according to the invention. The principal means for carrying out this method are: A binding mandrel 1, a holding and cutting appliance arranged substantially perpendicularly to the latter, and consisting of three jaws 2, 3, and 4, a separating member 5, and thread carriers or drivers, not shown, revolving round these members. In Figures 1 to 5 the two threads (primary threads) to be knotted together are denoted by *a* and *b*, and the ends thereof *a'* and *b'*.

According to the method of this invention the thread ends *a'* and *b'* are placed round the binding mandrel 1 and the cutting and holding appliance 2, 3, 4, as shown in Figure 1, by means of thread carriers revolving round these members.

the clip 15, and places it underneath the holding and cutting appliance round the latter, and also round the binding mandrel, as shown in Figures 1 to 4. At the commencement of this movement 5 the lever 11 is at the same time rocked, with the clip 33, 34, 35, 36, 37, into the position shown in dotted lines in Figure 11. During this movement it pulls the thread end *a'* out of the clip 16 and 10 brings it away over the holding and cutting appliance 2, 3, 4 to the other side of the thread guide within reach of the carrier 9, and in front of the movable jaw 29 of the thread guide 8, as shown in Figure 14. During the further rotation of the same the thread end *a'* is seized by the clip 27, 29 15 and pulled out of the clip 10, and both the thread ends are now carried along by the thread guide 8. They are guided through between the threads *a* and *b* (Figure 3 and Figure 8), and finally separated, as shown in Figure 3, by the separating member 5, which here has a shape somewhat different from that shown in Figures 1 to 5, and then, when the binding mandrel 1 is retracted in the direction C (Figure 17), are cut off by the scissors 3, 4, one thread end *b'* being gripped between the jaw 2 and the back 19 of the shearing blade 3.

In the first revolution of the thread guide 8 the thread *a* is pressed downwards gradually by the under side 45 of the helical thread guide, so that a 30 pull occurs therein, which draws in the loop 46 formed by it after the retraction of the mandrel (Figs. 3 and 4) and with it also pulls the thread *b* somewhat downwards (Fig. 8), so that the latter, after a complete revolution of the thread guide, 35 comes underneath the horn 24 and on the abutment 25. Since the thread *b* at this moment is firmly gripped both in the holding clip 13 and between the jaws 2 and 3 of the holding appliance, there is produced in the thread by the further movement of the abutment a tension which pulls 40 the loop 7 off the holding appliance and draws the knot that has been formed tight, as shown in Figure 5.

After the return of the moving parts into their 45 initial position by means of a pull-back spring hereinafter described, the threads *a* and *b* knotted together by a weaver's knot can be drawn out of the clips 13 and 14 without any entangling.

The driving of the apparatus as a whole is 50 effected by a thumb lever 44, which is rockable about a pivot 47, and which, through the medium of a link 48, a flexible band 49, and a disc 50, sets in rotation a shaft 51 (Fig. 12), from which the driving of all the moving parts proceeds. The shaft 51 carries a bevel wheel 52, which, through 55 a bevel wheel 53, sets in rotation a hollow shaft 54, the upper end 55 of which carries with a bracket 56 the thread guide 8. In the hollow shaft 54 is slidably supported a pull rod 57, which, with a pin 58, can move a toothed segment 60, which is rockable about the position 59. The toothed segment meshes with a pinion 61, which is mounted upon the shaft 38, and thereby drives the curved lever 11, as shown in Figure 11.

According to Figure 16 or 13, the pull rod 57 65 is hollow, and is provided with a pull-back appliance 62, which carries the binding mandrel 1. This pull back appliance, and also the pull rod 57, are controlled by a pin 63, which is mounted 70 on the bevel wheel 52, and which can slide in guides 64 and 65 in two controlling members 66 and 67. The latter are rockably supported at 68 and 69 and are connected by links 70 and 71 with the pull rod 57, and also with the pull-back appliance 62. To the control member 67 is further-

more pivoted a pull rod 72, which actuates the shearing member 3. A spiral spring 73, connected at one end with the bevel wheel 52 and at the other end with a bearing member, is stressed when the thumb lever 44 is depressed, and serves for 5 returning all the removable parts into their initial positions.

For the purpose of removing the cut-off thread ends there is provided at the lower end of the curved lever 11 a hook 74 (Figures 11 and 13), by 10 which the thread ends are seized during its return movement and conveyed downwards on to a member which is connected with the shaft 54 and revolves with the thread guide 8, for instance a cone 75 of sheet material which covers the gear 15 members. This cone brings the thread ends to the outside with a vane 76 through an aperture 77, shown in Figure 12, in the casing.

The thread clips, shown in Figures 14 and 15, are according to the invention so constructed 20 that the springs acting upon the gripping jaws have their points of application outside the abutments 31 and 35. This has the advantage that the threads entering the clips are reliably held therein. In Figure 15 is shown in dotted lines the 25 position of the movable gripping jaw 34 when the thread *a'* is put in. Since the spring pressure acts outside the stop 36, that is, in front of the latter, the thread cannot slip out of the clip so easily as is frequently the case with the known 30 clips.

The fixed backbone or framework of the apparatus is formed by a bearer 78, on which, or on extensions of which, the movable parts are 35 mounted. To it is also fitted a shackle 79 for securing the handle 39. The gear members are covered by an under portion 80 of the casing, and also by an upper casing member 81, carrying the parts 12 to 17 and 40 and 41.

What I claim is:—

1. An appliance for tying knots, more particularly weavers' knots, consisting of a withdrawable mandrel (1), and cutting and holding appliance (2, 3, and 4) arranged substantially perpendicularly to the mandrel, forming with the mandrel 45 two intersecting supporting members for the thread ends to be tied together, a thread guide rotatable about the mandrel, bearing two thread carriers (9), and being adapted to guide round the mandrel the ends of the threads to be knotted, a thread-introducing means, movable in an arc over the gripping and cutting appliance and adapted to place one thread end in front of one thread-carrier of the thread guide, and means for driving the appliance. 55

2. An appliance for tying knots, more particularly weavers' knots, consisting of a withdrawable mandrel (1), and a cutting and holding appliance (2, 3, and 4) arranged substantially perpendicularly to the mandrel, forming with the 60 mandrel two intersecting supporting members for the thread ends to be tied together, a thread guide of helical shape, rotatable about the mandrel, bearing two thread carriers (9), and being adapted to guide round the mandrel the ends of the threads to be knotted, a thread-introducing means, movable in an arc over the gripping and cutting appliance and adapted to place one thread end in front of one thread carrier of the thread 65 guide, and means for driving the appliance. 70

3. An appliance for tying knots, more particularly weavers' knots, consisting of a withdrawable mandrel (1), and a cutting and holding appliance (2, 3, and 4) arranged substantially perpendicularly to the mandrel, forming with the 75

- mandrel two intersecting supporting members for the thread ends to be tied together, a thread guide rotatable about the mandrel, bearing two thread carriers (9), and being adapted to guide round the mandrel the ends of the threads to be knotted, a thread introducing means, arranged inside the thread guide and formed of a curved lever (11) with a yielding clip (10) at the free end, and means for driving the appliance.
10. An appliance for tying a simple weavers' knot, consisting of a withdrawable mandrel (1), and a cutting and holding appliance (2, 3, and 4) arranged substantially perpendicularly to the mandrel, forming with the mandrel two intersecting supporting members for the thread ends to be tied together, a thread guide rotatable about the mandrel, bearing two thread carriers (9), and being adapted to guide round the mandrel the ends of the threads to be knotted, a thread introducing means, movable in an arc over the gripping and cutting appliance, a separating member (5, 6), extending partly in the plane of the cutting and holding appliance and partly parallel to the mandrel, and adapted to prevent one thread end (a') from entering the cutting and holding appliance, and means for driving the appliance.
15. An appliance for tying a simple weavers' knot, consisting of a withdrawable mandrel (1), and a cutting and holding appliance (2, 3, and 4) arranged substantially perpendicularly to the mandrel, composed of two cutting jaws (3, 4) and a gripping jaw (2), the latter being shorter than the cutting jaw, a thread guide rotatable about the mandrel, with two thread carriers (9), a thread introducing means movable in an arc, a separating member (5, 6), extending partly in the plane of the cutting and holding appliance and partly parallel to the mandrel, and adapted to prevent one thread end (a') from entering the cutting and holding appliance, and means for driving the appliance.
20. An appliance for tying knots, more particularly weavers' knots, consisting of a withdrawable mandrel (1), and a cutting and holding appliance (2, 3, and 4) arranged substantially perpendicularly to the mandrel, forming with the mandrel two intersecting supporting members for the thread ends to be tied together, a thread guide rotatable about the mandrel, carrying a double clip as a thread carrier (9), with four superposed gripping jaws (26, 28 and 29, 27), and being adapted to guide round the mandrel the ends of the threads to be knotted, a thread-introducing means, movable in an arc over the gripping and cutting appliance and adapted to place one thread end in front of one thread carrier of the thread guide, and means for driving the appliance.
25. An appliance for tying knots, more particularly weavers' knots, consisting of a withdrawable mandrel (1), and a cutting and holding appliance (2, 3, and 4) arranged substantially perpendicularly to the mandrel, forming with the mandrel two intersecting supporting members for the thread ends to be tied together, a thread guide rotatable about the mandrel, carrying a double clip as a thread carrier (9), with four superposed gripping jaws (26, 28 and 29, 27), and being adapted to guide round the mandrel the ends of the threads to be knotted, a thread-introducing means, movable in an arc over the gripping and cutting appliance and adapted to place one thread end in front of one thread carrier of the thread guide, and means for driving the appliance.
30. An appliance for tying knots, more particularly weavers' knots, consisting of a withdrawable mandrel (1), and a cutting and holding appliance (2, 3, and 4) arranged substantially perpendicularly to the mandrel, forming with the mandrel two intersecting supporting members for the thread ends to be tied together, a thread guide rotatable about the mandrel, carrying a double clip as a thread carrier (9), with four superposed gripping jaws (26, 28 and 29, 27), and being adapted to guide round the mandrel the ends of the threads to be knotted, a thread-introducing means, movable in an arc over the gripping and cutting appliance and adapted to place one thread end in front of one thread carrier of the thread guide, and means for driving the appliance.
35. An appliance for tying knots, more particularly weavers' knots, consisting of a withdrawable mandrel (1), and a cutting and holding appliance (2, 3, and 4) arranged substantially perpendicularly to the mandrel, forming with the mandrel two intersecting supporting members for the thread ends to be tied together, a thread guide rotatable about the mandrel, carrying a double clip as a thread carrier (9), with four superposed gripping jaws (26, 28 and 29, 27), and being adapted to guide round the mandrel the ends of the threads to be knotted, a thread-introducing means, movable in an arc over the gripping and cutting appliance and adapted to place one thread end in front of one thread carrier of the thread guide, and means for driving the appliance.
40. An appliance for tying knots, more particularly weavers' knots, consisting of a withdrawable mandrel (1), and a cutting and holding appliance (2, 3, and 4) arranged substantially perpendicularly to the mandrel, forming with the mandrel two intersecting supporting members for the thread ends to be tied together, a thread guide rotatable about the mandrel, carrying a double clip as a thread carrier (9), with four superposed gripping jaws (26, 28 and 29, 27), and being adapted to guide round the mandrel the ends of the threads to be knotted, a thread-introducing means, movable in an arc over the gripping and cutting appliance and adapted to place one thread end in front of one thread carrier of the thread guide, and means for driving the appliance.
45. An appliance for tying knots, more particularly weavers' knots, consisting of a withdrawable mandrel (1), and a cutting and holding appliance (2, 3, and 4) arranged substantially perpendicularly to the mandrel, forming with the mandrel two intersecting supporting members for the thread ends to be tied together, a thread guide rotatable about the mandrel, carrying a double clip as a thread carrier (9), with four superposed gripping jaws (26, 28 and 29, 27), and being adapted to guide round the mandrel the ends of the threads to be knotted, a thread-introducing means, movable in an arc over the gripping and cutting appliance and adapted to place one thread end in front of one thread carrier of the thread guide, and means for driving the appliance.
50. An appliance for tying knots, more particularly weavers' knots, consisting of a withdrawable mandrel (1), and a cutting and holding appliance (2, 3, and 4) arranged substantially perpendicularly to the mandrel, forming with the mandrel two intersecting supporting members for the thread ends to be tied together, a thread guide rotatable about the mandrel, carrying a double clip as a thread carrier (9), with four superposed gripping jaws (26, 28 and 29, 27), and being adapted to guide round the mandrel the ends of the threads to be knotted, a thread-introducing means, movable in an arc over the gripping and cutting appliance and adapted to place one thread end in front of one thread carrier of the thread guide, and means for driving the appliance.
55. An appliance for tying knots, more particularly weavers' knots, consisting of a withdrawable mandrel (1), and a cutting and holding appliance (2, 3, and 4) arranged substantially perpendicularly to the mandrel, forming with the mandrel two intersecting supporting members for the thread ends to be tied together, a thread guide rotatable about the mandrel, carrying a double clip as a thread carrier (9), with four superposed gripping jaws (26, 28 and 29, 27), and being adapted to guide round the mandrel the ends of the threads to be knotted, a thread-introducing means, movable in an arc over the gripping and cutting appliance and adapted to place one thread end in front of one thread carrier of the thread guide, and means for driving the appliance.
60. An appliance for tying knots as claimed in claim 6, with a double clip, in which a spring member (32) is so arranged that the latter presses outside the thread stop (31) upon the movable gripping jaws (28, 29).
65. An appliance for tying knots as claimed in claim 3, with a yielding clip (10) on the curved lever (11), in which a spring (35) is so arranged that it presses outside the thread stop (36) upon one movable gripping jaw (34).
70. An appliance for tying knots, more particularly weavers' knots, consisting of a withdrawable mandrel (1), and a cutting and holding appliance (2, 3, and 4) arranged substantially perpendicularly to the mandrel, forming with the mandrel two intersecting supporting members for the

thread ends to be tied together, a thread guide of helical shape, rotatable about the mandrel, having a horn (24) at the upper end, with a stop (25) on its under side, the latter being adapted to tension one thread (b) and thereby pulling the formed knot off the cutting and holding appliance and pulling the knot together, a thread introducing means (10, 11) movable in an arc, and means for driving the appliance.

10. An appliance for tying knots, more particularly weavers' knots, consisting of a withdrawable mandrel (1), and a cutting and holding appliance (2, 3, and 4) arranged substantially perpendicularly to the mandrel, a thread guide rotatable about the mandrel, bearing two thread carriers (9), and being adapted to guide round the mandrel the ends of the threads to be knotted, a thread introducing means, movable in an arc over the gripping and cutting appliance, a separating member (41) and a separating arm (12), arranged substantially in a plane parallel to the mandrel (1), and adapted to separate the two threads upon introduction into the appliance, and means for driving the appliance.

11. An appliance for tying knots as claimed in claim 10, in which, at one end of the separating arm, a cutting-off appliance is provided, consisting of two interengaging circular knives.

12. An appliance for tying knots, more particularly weavers' knots, consisting of a withdrawable mandrel (1), a fixedly arranged holding arm (22) adapted to support the tip of the mandrel, a cutting and holding appliance (2, 3, and 4) arranged perpendicularly to the mandrel, a thread guide rotatable about the mandrel, bearing two thread carriers (9), and being adapted to guide round the mandrel the ends of the threads to be knotted, a thread introducing means, movable in an arc over the gripping and cutting appliance, and adapted to place one thread end in front of one thread carrier of the thread guide, and means for driving the appliance.

13. An appliance for tying knots, more particularly weavers' knots, consisting of a withdrawable mandrel (1), and a cutting and holding appliance (2, 3, and 4) arranged substantially perpendicularly to the mandrel, forming with the mandrel two intersecting supporting members for the thread ends to be tied together, a thread guide rotatable about the mandrel, bearing two thread carriers (9), and being adapted to guide round the mandrel the ends of the threads to be knotted, a thread introducing means, movable in an arc over the gripping and cutting appliance, a carrier (78) for supporting the said members, a handle (39) secured to the said carrier, and a driving lever (44) adapted to be actuated by the thumb of the hand.

14. An appliance for tying knots as claimed in claim 13, in which a vertical driving shaft (54, 55), carrying the thread guide (8) is provided, in which are arranged a longitudinally displaceable hollow pull rod (57) for moving the thread introducing means (10, 11), and in the latter a pull rod (62) carrying the mandrel (1), means also being provided which transmit the movement of the driving lever (44) to the driving shaft and the two pull rods.

15. An appliance for tying knots, more particularly weavers' knots, consisting of a withdrawable mandrel (1) and a cutting and holding appliance (2, 3, and 4) arranged substantially perpendicularly to the mandrel, a thread guide rotatable about the mandrel, bearing two thread carriers (9), a curved thread-placer (11), with a

clip (10) at the upper end, rockably arranged inside the thread guide, and having at the lower end a hook (74), adapted when the thread placer rocks back into its initial position to seize the 5 cut-off thread ends and convey them downwards, a revolving member underneath the thread placer, adapted to seize the thread ends conveyed by the latter and eject them, and means for driving the appliance.

16. An appliance for tying knots as claimed in claim 15, in which the revolving member consists of a sheet metal cone (75) revolving with the thread guide (8), and is at the same time adapted to cover driving members of the appliance. 5

PROTECTING OF LIGHT METALS

Leo Rosenthal, Leverkusen-Wiesdorf, and Reinhard Hebermehl, Cologne-Deutz, Germany, assignors to I. G. Farbenindustrie Aktiengesellschaft, Frankfort-on-the-Main, Germany

No Drawing. Application September 26, 1934,
Serial No. 745,646. In Germany October 3,
1933

7 Claims. (Cl. 91—68)

The present invention relates to light metals coated with a layer of chlorinated rubber.

It is known that light metals suffer from the disadvantage of being easily attacked by mechanical influences and of being corroded by chemically active substances and even by moist air. Considering the fact that light metals are employed in airships, aeroplanes, automobile cars a. s. o. on a large scale, it is of great importance to 10 do away with this disadvantage in order to avoid accidents.

It is the object of our present invention to overcome these difficulties by protecting the surface of the light metals by the application of a layer of 15 chlorinated rubber, this substance being very resistant towards mechanical and chemical affects. However, it has been found that a layer of chlorinated caoutchouc does not adhere sufficiently well to the light metals for securing protection of 20 the latter which meets every practical demand. The problem of securing adhesion of the chlorinated rubber to the light metals has now been solved by the application of an intermediate layer consisting of or containing a water-insoluble product 25 of the polymerization of such carboxylic acid derivatives as contain the grouping $\text{CH}_2=\text{C}=$. The objects of our present invention are, therefore, light metals being coated with a layer of chlorinated rubber and having interposed therebetween a 30 layer of polymerization products of the character described. Still another feature of our invention is the provision of pigments in the priming coating, it being the preferred form of our invention to employ pigments of a basic nature

35 such as zinc white, red lead and the like, as the latter give the best results with regard to a firm adhesion of the chlorinated rubber to the priming coating and, through the cooperation of the priming coating, to the light metals. As polymerization products of the character described, there may be mentioned, for instance, polyvinyl- 40 esters such as polyvinylacetate, polyvinylchloracetate, polyvinylpropionate, polyvinylester of benzoic acid, furthermore polymeric acrylic acid 45 esters such as methyl or ethyl ester, polymeric acrylic acid nitril, and finally the products of the conjoint polymerization of vinyl- and acrylic acid derivatives of the character described, such as mixed polymerization products of vinyl acetate 50 and an ethylester of acrylic acid. We wish to point out that these polymerization products can furthermore be employed in mixture with each other and/or in combination with other film-forming compounds such as nitrocellulose, cellulose ethers, softening agents or resins, it being 55

understood that chlorinated rubber may likewise be present in the priming coating. The primer is applied to the light metals, for instance, in the form of lacquers which contain volatile solvents, whereupon, after drying, the chlorinated-rubber-containing protective coating is applied. We wish it to be understood that the protective layer of chlorinated rubber may likewise contain addition products such as softening agents regardless as to whether they are saponified by the influence 10 of acid or alkaline reacting substances or not; as examples for the latter, there may be mentioned, for instance, chlorinated diphenyl, alkylated or aralkylated naphthalenes or the oily sulfur containing reaction product of toluene or xylene with 15 sulfur in the presence of aluminium chloride. As examples for saponifiable softening agents, we mention tricresylphosphate, dibutylphthalate and the like.

Our present invention is not restricted to the 20 protecting of a single light metal, but can be applied to any light metal such as aluminium or magnesium or alloys of the same. As to the chlorinated rubber, every product may be employed, provided that it is soluble in organic solvents. 25

The following examples illustrate the invention, the parts being by weight:—

Example 1

An aluminium sheet is furnished with a priming coating by applying thereto by brushing, spraying etc. a lacquer of the following composition:

	Parts
Polymerized vinylacetate	15 35
Zinc white	10
Ethylacetate	35
Toluene	20
Xylene	20
	40

After drying, there is applied the protective coating by means of a lacquer of the following composition:

	Parts
Chlorinated caoutchouc of a chlorine content of about 64%	45
Toluene	20
Xylene	40
Tricresylphosphate	6-8
Butylstearate	4
Aluminium bronze	10 50

In the above given example, the lacquer employed for the application of the priming coating may, furthermore, contain 1 to 2 parts of phthalic acid butylester or tricresylphosphate whereas the 55
